(57) **CLAIM**

We claim the ornamental design for a cooking vessel, as shown and described.

DESCRIPTION

The patent or application file contains at least one drawing executed in color. Copies of this patent or patent application publication with color drawing(s) will be provided by the Office upon request and payment of the necessary fee.

FIG. 1 is an isometric view, from the front top right, of the cooking vessel.

FIG. 2 is an isometric view, from the back bottom left, of the cooking vessel.

FIG. 3 is a plan view from the top of the cooking vessel.

FIG. 4 is a plan view from the bottom of the cooking vessel.

FIG. 5 is an elevation view from the front of the cooking vessel.

FIG. 6 is an elevation view from the back of the cooking vessel.

FIG. 7 is an elevation view from the right of the cooking vessel; and,

FIG. 8 is an elevation view from the left of the cooking vessel.

The broken lines showing portions of the article form no part of the claimed design.
